PLASTER APPLYING MECHANISM

Abe Salman and Malcolm B. Bartlett, Cincinnati,
Ohio; said Bartlett assignor to said Salman

Application June 13, 1945, Serial No. 599,254

15 Claims. (CL. 72—130)

1

Our invention relates to mechanical means for applying plastic or semi-plastic coating material to surfaces which may range from horizontal to vertical. Designed primarily as a means for applying plaster to the walls and ceilings of buildings, our structure is capable of other uses, and may be employed for applying other substances.

An object of our invention is the provision of a successful mechanism for progressively applying controlled coatings of plastic to such surfaces as walls.

It is our object to provide a mechanism which is readily portable, readily assembled, and easily installed or set up to function in any one position with great accuracy. It is our object to provide a mechanism which may be adjusted from position to position quickly and accurately.

Devices for applying plastics to walls, herein-after referred to as plastering machines, have hitherto been suggested, but have not proved successful. Yet it has been known that substantial savings as well as a more uniform result could be realized with very much less labor if the bulk of the plaster, at least, could be applied by machine. There are numerous problems involved in the provision of operative mechanism to this end, and important objects of the invention relate to the solution of these problems, as will hereinafter become apparent.

These and other objects of our invention which will be apparent to one skilled in the art upon reading these specifications or will be made clear as the description proceeds, we accomplish by that construction and arrangement of parts of which we will now describe an exemplary embodiment. Reference is made to the drawings which form a part hereof, and in which:

Fig. 1 is a side elevation of our machine.

Figs. 2, 3, 4, and 5 are partial sectional views thereof taken on correspondingly numbered section lines in Fig. 1.

Fig. 6 is a partial sectional view taken on the line 6—6 of Fig. 7.

Fig. 7 is a view similar to Fig. 1, but with the mechanism in a partially elevated position.

Fig. 8 is a sectional view taken on the line 8—8 of Fig. 7.

Fig. 9 is a plan view of our machine.

Fig. 10 is a sectional view of the head mechanism taken on the line 10—10 of Fig. 9.

Fig. 11 is a partial sectional view thereof, taken on the line 11—11 of Figure 10.

In the practicing of our invention we deliver the plastic material to the surface under pressure through a nozzle. The nozzle has mechani-

2

cal mounting and actuating means hereinafter referred to as a head. The nozzle is so mounted and actuated by the head and mechanism therein that it is caused mechanically to perform a traversing operation. Thus with the head stationary, the mounting and actuating means is capable of causing the nozzle to move in such fashion that the delivery end of it has a straight line traverse in a direction parallel with one edge of the frame or head. The extent of this traverse may be varied not only by design and construction of the head itself but also by the length of time during which the actuating means is moved. The nozzle is of substantial width in one direction and at each side edge it bears smoothing plates appropriately mounted. Means are provided to cause one or the other of these smoothing plates to move out of the way at each end of the traverse of the nozzle on the head, the purpose of this being to permit the nozzle to enter and conform closely to corners between walls.

The head is mounted in a portable frame which is set up in parallelism to a vertical surface to be plastered, and is moved sidewise from time to time as may be required. The head has power actuated movement in the frame. The combination of the two movements mentioned—the movement of the nozzle with respect to the head and the movement of the head with respect to the frame—which determines the length of the over-all stroke of the machine and, without other adjustment, may be varied by controlling the movement means for either or both of these instrumentalities. The movement of the nozzle with respect to the head and the movement of the head with respect to the frame are preferably though not necessarily concurrent. Thus we are enabled, for example, so to operate our mechanism that the nozzle, starting at the corner formed by the floor with the side wall of the building, can apply a continuous vertical stripe of plaster from that corner to the corner formed by the wall and the ceiling, the width of the stripe depending upon the width of the nozzle.

When such a stripe has been formed, the frame may be moved sidewise so as to prepare the mechanism for the application of an adjacent vertical stripe.

The head may be relocated in the frame in such manner as to apply plaster to wall sections in other than vertical positions including horizontal wall sections such as ceilings. One feature of our equipment is that the traverse of the nozzle with respect to the head is a traverse of

very considerable length, being in practice 4 feet or thereabouts, although this may be varied. Hence it becomes possible and economical to plaster non-vertical areas such as ceilings while the frame of the device is vertical and stationary and while the head is stationary with respect to the frame. It is possible, however, to support our frame in such a way that it parallels non-vertical walls so that the length of the traverse may be extended.

It is also to be noted that because of the provision of a head with respect to which the nozzle has a traverse of very substantial length and because of the provision for the movement of the head with respect to the frame, we are enabled to provide a mechanism which without disassembly and rearrangement or structural lengthening can be caused to apply plaster on vertical walls from the floor to the ceiling for all of the varying wall heights reasonably to be expected in any particular class of building construction.

Referring first to Figures 9 and 10, we have shown a head in the form of a frame of spaced members 10. At one side of the structure the spaced members diverge to form parts more remote from each other, each such part presenting an outer edge 11 serving, as hereinafter set forth, as a trackway. The head is suitably braced as may be required, and can be constructed in any suitable fashion. For example, it may be a single casting, or it may be fabricated from individual members.

On the rear edge of the head we mount an ear or ears 12 which bear a pivot shaft 13 passing through a slot 14 in an arm 15 which may, if desired, be of bifurcated construction as shown. The arm also bears a shaft 16 which engages in the slot of a fork member 17. The other end of this member is perforated and threaded to accept a threaded shaft 18 journaled as at 19 and 20 in bearings on the head. The shaft 18 being rotatable but held against movement lengthwise in its bearings, it will be evident that rotation of the shaft will cause the fork member 17 to move up or down depending upon the direction of rotation. Since also the fork member 17 engages the shaft 16 of the arm 15, it will be evident that the arm will be rocked angularly during such movement of the fork member.

The head is provided with one or preferably two cam tracks 21. On the ends of the arm shaft 16 we mount cam following rollers 22 which ride in the cam tracks. The cam tracks are so shaped as to move the arm 15 lengthwise during its rocking motion already referred to and in such manner that the end of a nozzle mounted upon the arm follows a straight line or uni-planar path throughout the swinging movement of the arm.

A nozzle member 23 is bolted or otherwise attached to the arm 15. From the place of attachment the nozzle flares outwardly laterally as shown in Figure 9 but becomes narrower in the opposite direction as shown in Figure 10. Hence the nozzle outlet is of slot shaped form, having considerable length and a very much smaller transverse dimension. The flange means 24 by which the nozzle is attached to the arm is prolonged as at 24a (Figure 9) and the adjacent portion 23a of the nozzle is enlarged sidewise so as to provide for connecting a flexible tubing 25 to the nozzle in communication with its interior so that plaster may be delivered to the nozzle under pressure. The nozzle end carries a pair of smoothing plates 26 and 27 hinged to it at their ends as at 28. Each of these smoothing plates has

arms 29 or 30 bearing roller means 31. The arms are so positioned that as the nozzle is moved up and down by the arm, the roller means 31 engage and ride along the track ways 11 on the head extensions. These trackways lie parallel to the path of movement of the outer end of the nozzle. Hence the trackways, rollers and arms serve to keep the smoothing plates in a fixed relation to the surface to which plaster is being applied throughout the extent of the trackways. This relationship with the surface being treated is maintained in spite of the tilting of the nozzle 23 as it moves up or down, as will be evident.

The smoothing plates may be arranged so as to be coplanar and parallel; but we prefer so to arrange them that they slant outwardly from the nozzle end toward the wall so that they assist in forcing the plaster toward the wall during their movement with the nozzle, thus helping to key the plaster into the interstices of the plaster receiving support, e. g. lathing.

However, the traverse of the nozzle end extends beyond the ends of the trackways 11 so that, in both the upper and lowermost nozzle positions as shown in Figure 10, one or the other set of arms 29, 30 rides over the end of the trackways 11 so as to permit the plate to which such arms are attached to swing into a horizontal position or a position at which it lies substantially at right angles to the other smoothing plate which is still being positioned by the trackways. This is illustrated for uppermost and lowermost positions in dotted lines in Figure 10, and it will be apparent that when the nozzle is in its uppermost position the uppermost smoothing plate has swung to the horizontal so that the nozzle can get up into the corner formed between a vertical wall and a ceiling. Similarly in the lowermost position the nozzle is enabled to get down into a corner between a vertical wall and a floor.

In order to cause the arms to follow the trackways 11 and adjacent portions of the head frame, we provide means for resiliently urging the arms against the trackways. One such means comprises a coiled tension spring 32 interconnecting the smoothing plates 26 and 27 and passing through a lined orifice 33 in the nozzle. The closed walls of the orifice do not interrupt the flow of plastic material through the nozzle body but on the contrary serve in part at least to distribute the flow. Vanes and other distributors may be included within the body of the nozzle if that be found desirable.

On the end of the threaded shaft 18 we have shown a bevel gear 34. This meshes with another bevel gear 35 mounted on a shaft 36 journaled in the head. To the shaft 36 we attach a power means such as an electric motor either directly or through the intermediary of a suitable gear box or speed reducer. The motor is to be found at 120 in Figures 9 and 10. The motor is a reversible motor capable of rotating the threaded shaft 18 in either direction as desired. It is preferably equipped with adjustable automatic switch means serving to cause it to operate in a given direction at speed for a given length of time. Upon the actuation of a starting switch the limit switch mechanism may thus be set to produce automatically a traverse of the nozzle from the lowermost dotted line position in Figure 10 to the uppermost dotted line position and there stop the traverse. A reversing switch may be employed to produce traverse of the nozzle in the opposite direction and may be controlled by the same limit

switch or another for preventing overrunning, as will be understood.

It will now be seen that the mechanism thus far described, if supported with the trackways parallel to a surface to which plastic is to be applied, is capable of producing a substantial traverse of the nozzle, keeping the nozzle end moving in parallelism with the surface throughout the traverse and, if plastic be supplied to the nozzle at the proper rate through the tubing 25, is capable of applying that plastic to the said surface in a stripe determined in width by the longer dimension of the nozzle end and in length by the length of nozzle traverse. Furthermore, at each end of such stroke the nozzle is capable of entering corners between the said surface and another. The smoothing plates are continuously active throughout the traverse, one or the other being automatically drawn out of the way at the ends of the traverse. The longer dimension of the nozzle end may be varied, as will be evident; and the structure of the head may be changed to vary the length of the stroke. In an exemplary machine our head and nozzle combination applies a stripe of plaster approximately 2 feet in width in a stroke approximately 4 feet in length.

We mount our head with respect to a framework in which the head as such is longitudinally movable. The extent of movement of the head in the frame is thus added to the extent of movement of the nozzle with respect to the head in such fashion that the effective length of the nozzle stroke is the sum of the two.

Our frame construction is illustrated in Figures 1 to 8 inclusive. On a suitable base 31 we mount four uprights 38, 39, 40 and 41. The base may be a cast member having integral sockets or the like (not shown) to receive the ends of the uprights and hold them firmly in the vertical position. The base 31 may be provided with casters or the like 43, 44, 45 and 46, upon which the frame may be moved. It is within the purview of our invention to provide track means, for example, along the floor of a room parallel to a side wall and cause the casters 43, 44, 45 and 46 to move along the trackway to facilitate the lateral movement of the frame during a job of plastering. This is not, however, generally necessary; and the frame may be moved about upon the floor of a building on the casters or upon skids, where casters are not employed. Especially where casters are employed, we prefer to provide a means for affixing our frame in a selected position on the floor so that it will not move during the course of a plastering stroke. Many such locking means may be employed and will suggest themselves to skilled workers in the art. In practice we perforate the base 31 at the bottom of one or more of the uprights 38, 39, 40 and 41 (which are in the form of hollow members, e. g. pieces of pipe) and pass a threaded rod down through such members engaging it in the perforation in the base which is also threaded. The upper ends of such rods may be squared or otherwise prepared for the attachment of a wrench so that after the frame has been located in the desired position on a floor these threaded rods may be lowered so as to engage the floor and frictionally prevent movement of the frame. Such threaded rods, if provided as described at the corners of the structure, are also useful in leveling it up where the floor is characterized by unevennesses or the plane of it is not perpendicular to the plane of the side wall to be plastered. The threaded rod construction has not been ill-

lustrated in the drawings but will be readily understood by the skilled worker in the art in the light of our description.

The base 31 holds the upright in spaced relationship at the bottom. At the top adjacent pairs of the uprights are spaced and fastened together by bridge members indicated in the several figures at 47 and 48.

The uprights 38, 39, 40 and 41 serve as ways 10 upon which subframe members are slidable. These subframes comprise members 49, 50 and 51 on each side. Each of these members is in the form of an elongated loop-shaped element the end inside surfaces of which engage and slide along the uprights. The elements 49, 50 and 51 are interconnected vertically by elements 52 and 53. These elements are conveniently in the form of angle irons attached to squared corner portions of the transverse sliding members 49, 50 and 51 as indicated in the several figures at 49a, 50a and 51a. Inner side edges of these angle irons project beyond the squared corner portions 49a, etc. so as to provide trackways upon which a head supporting means is vertically slidable.

25 The head supporting means comprises end plates 54 and 55, the side edges of which are grooved (as most clearly shown in Figures 6 and 9) to receive the edges of the angle irons 52 and 53. The plates 54 and 55 may be interconnected by a plurality of rod members 56, 56', 57, 58, 59, 60 and 61. The head is mounted with respect to several of these rods as hereinafter explained.

We thus have a main frame comprising the uprights 38, 39, 40 and 41 upon which subframe members are vertically slidable, a head support being vertically slidable upon the subframe. The bodily movement of the head (attached to the head support) will thus be the sum of the traverses of the head support and the subframe 40 with respect to the main frame and to each other.

We mount a motor 62 on the base 31 and connect it by a suitable drive 63 to a gear box or like speed reducer 64 also mounted on the base. The speed reducer is connected by a drive 65 to a shaft 66 journaled on the base in suitable bearings, one of which is shown at 67 in Figure 1. The ends of the shaft 66 carry sheaves 68 and 69 for vertical endless belts, chains or the like at either side of the machine. One of these vertical flexible means is shown in Figure 1 at 70. It passes over a sheave 71 suspended by means of a fork 72 and a rod 73 from the bridge member 47. A similar construction is provided at the opposite side of the machine with the upper sheave similarly suspended from the bridge 48.

At one point the flexible member 70 is anchored to the subframe on its side as indicated at 74 in Figures 1 and 7. The opposite flexible member is similarly anchored to the opposite subframe. It will now be understood that as the shaft 66 is rotated in a clockwise direction (Figure 1) the subframes are raised. They will be lowered if the shaft is rotated in a counter-clockwise direction.

We also mount sheaves, one of which is shown at 75 in Figures 1 and 7, in suitable bearing members on the lowermost transverse elements 51 of the subframes. Flexible endless means such as belts, chains, or the like extend from these sheaves to sheaves 76 and 77 mounted on or suspended from the top members 49 of the subframes. In Figures 1 and 7 we have shown the sheave 76 suspended by a fork 77 and a rod 78 from the member 49.

One of the flexible elements is indicated in these figures at 79. This flexible element is indicated as anchored at 80 to a bracket 81 affixed to the upright 38. The flexible element 79 is also anchored as at 82 to the end plate 54 of the head support. A similar construction is employed upon the opposite side of the machine.

As the subframes are moved upwardly, they carry with them the sheaves such as 75 and 76; but since the flexible element 79 is anchored at 80, it is caused effectively to run around the sheaves, rotating them. Also since the flexible element 79 is anchored as at 82 to the side plate of the head support, an upward movement of the subframe causes an upward movement of the head support at double the speed and for double the distance. If the subframe members are thus caused to move upwardly 2 feet, the head support will be caused to move upwardly 4 feet.

The over-all height of the base plus the uprights 38, 39, 40 and 41 is preferably chosen to be such that the apparatus may be readily moved about and passed through doorways of regulation height without tilting. The subframe members are substantially shorter than the over-all length of the main frame. The subframe members are capable of sliding up to the top and beyond the top of the main frame supports. The end plates 54, 55 of the head support are capable of sliding through the length or even beyond the upper ends of the subframe members. Hence the total traverse of the head support can be made very substantially greater than the total length of the uprights 38, 39, 40 and 41. Thus the over-all height of our frame apparatus when the subframes and head support are in lowered position can be kept short, say, not more than 6 to 7 feet, while the total traverse of the nozzle may be up to 11 or 12 feet, giving us an ample traverse for buildings of the dwelling class as well as usual buildings of other classes. Needless to say, our frame construction can be elongated for other uses and other types of buildings, as well as for outside work as in stuccoing the exterior of buildings.

The motor 62 is preferably provided with limit switch mechanism such as that described above in connection with the motor for the head, the limit switch mechanism being adjustable to control the over-all length of stroke of the head support with respect to the main frame to a value which, added to the stroke of the nozzle on the head will provide the desired length of plastering stroke. It is not necessary that the head motor be actuated at the same time as the motor 62. By the provision of suitable switches the stroke may be made separate and sequential. We prefer, however, to make them simultaneously because smoothness of operation is promoted in this way. The nozzle may start at the floor line in the lowermost position shown in dotted lines in Figure 10 and in a continuous sweep upwardly produced concurrently by the movement of the nozzle with respect to the head and the movement of the head with respect to the main frame, it may end the stroke at the ceiling line in the position shown in the uppermost dotted lines in Figure 10.

The head is demountable from the head support and the arrangement of the several head support rods is such that the head may be mounted upon the head support in the position shown in Figure 3 for the plastering of vertical surfaces, or in a position at right angles thereto

for the plastering of overhead horizontal surfaces.

The head is mounted upon rod 58 by means of an ear on the head indicated at 121 in Figure 10. In the position shown in that figure, the head rests against rod 57 at its back, and against rod 61 on the bottom, being held down by rod 56' at the top. Rod 56 is not in place. When it is desired to change the position of the head, rod 56' is removed, and the head swung upwardly on rod 58 as a pivot until it comes against rod 59. Rod 56 is then inserted to prevent reverse swinging of the head, and rod 56' is reinserted to assist in holding it in place.

When horizontal overhead surfaces are to be plastered, the head may be swung, as described, with respect to the head support and a portion of the overhead surface plastered in a single stroke, the length of which is the length of stroke of the nozzle with respect to the head as produced by the head motor. In this event, the subframes and head support are employed to fix the height of the head, but are not moved during the plastering stroke. It is possible, however, to dispose our frame mechanism horizontally on suitable supports (not shown but readily understood) by which it may be located parallel to and the proper distance from an overhead horizontal surface and use our frame construction and its motive mechanism to increase the length of stroke of the nozzle just as in plastering vertical surfaces. Also with a suitable trackway or on a level floor, the frame may be moved either along a wall or away from it. It is likewise possible to suspend our frame horizontally above a floor and employ our mechanism for laying plastic type or cementitious flooring.

Modifications may be made in our invention without departing from the spirit of it. Having thus described our invention, what we claim as new and desire to secure by Letters Patent is:

1. In a means for applying plastics to surfaces, a head mechanism comprising a framework, a pin mounted in said framework, a slotted arm 45 slidable and rotatable on said pin, means for imparting to said arm a rocking movement about said pin, a nozzle having an orifice attached to said arm through which plastic material may be forced, and cam means for guiding said arm and 50 acting to slide it on said pin during its rocking movement to keep said orifice of said nozzle moving in a flat plane.

2. The apparatus claimed in claim 1 in combination with means for supporting said head adjacent a surface to which plastic is to be applied with the plane of movement of the nozzle orifice parallel to said surface, and means for supplying plastic under pressure to said nozzle.

3. In a means for applying plastics to surfaces, 60 a head mechanism comprising a framework, a pin mounted in said framework, a slotted arm 65 slidable and rotatable on said pin, means for imparting to said arm a rocking movement about said pin, a nozzle having an orifice attached to said arm through which plastic material may be forced, and cam means for guiding said arm and acting to slide it on said pin during its rocking movement to keep said orifice of said nozzle moving in a flat plane, said frame having a portion

70 with an edge paralleling the plane of movement of said nozzle orifice, smoothing plates pivoted to said nozzle orifice on each side thereof, said smoothing plates having means for contacting said edge whereby said smoothing plates are kept 75 with surfaces in said plane of movement of the

nozzle orifice, said edge terminating at the ends of the path of movement of said nozzle orifice and joining other surfaces whereby in extreme positions of said nozzle orifice one of said smoothing plates will ride over the end of said edge onto said adjacent surface bringing said smoothing plate to a position substantially at right angles to the other smoothing plate.

4. In a plastering machine, a head mechanism comprising spaced members, a slotted arm lying therebetween and pivoted on means passing through the slot in said arm and fixed in said members, a threaded shaft journaled on said members and bearing a nut with a slotted extension, a pivot on said arm engaging in said slotted extension whereby movement of the nut along the shaft will cause said arm to rock about said first mentioned pivot, a cam track in one at least of said members in which said last mentioned pivot on said arm engages, a nozzle on the end of said arm remote from said first pivot, said cam track acting to produce longitudinal movement of said arm with respect to said first mentioned pivot during its rocking motion thereabout whereby the orifice of said nozzle follows a path lying in a flat plane, and means for rotating said shaft so as to produce rocking movement of said arm so that when plastic material is forced through said nozzle it is applied thereby to a wall or the like to form a coating thereon with a surface lying in said plane.

5. In a plastering machine, a head mechanism comprising spaced members, a slotted arm lying therebetween and pivoted on means passing through the slot in said arm and fixed in said members, a threaded shaft journaled on said members and bearing a nut with a slotted extension, a pivot on said arm engaging in said slotted extension whereby movement of the nut along the shaft will cause said arm to rock about said first mentioned pivot, a cam track in one at least of said members in which said last mentioned pivot on said arm engages, a nozzle on the end of said arm remote from said first pivot, said cam track acting to produce longitudinal movement of said arm with respect to said first mentioned pivot during its rocking motion thereabout whereby the orifice of said nozzle follows a path lying in a flat plane, and means for rotating said shaft so as to produce rocking movement of said arm so that when plastic material is forced through said nozzle it is applied thereby to a wall or the like to form a coating thereon with a surface lying in said plane, said nozzle orifice being of small dimension in the direction of motion of said arm and being extended transversely so as to apply plastic material in a wide stripe.

6. In a plastering machine, a head mechanism comprising spaced members, a slotted arm lying therebetween and pivoted on means passing through the slot in said arm and fixed in said members, a threaded shaft journaled on said members and bearing a nut with a slotted extension, a pivot on said arm engaging in said slotted extension whereby movement of the nut along the shaft will cause said arm to rock about said first mentioned pivot, a cam track in one at least of said members in which said last mentioned pivot on said arm engages, a nozzle on the end of said arm remote from said first pivot, said cam track acting to produce longitudinal movement of said arm with respect to said first mentioned pivot during its rocking motion thereabout whereby the orifice of said nozzle follows a path lying in a flat plane, and means for rotating said shaft so

as to produce rocking movement of said arm so that when plastic material is forced through said nozzle it is applied thereby to a wall or the like to form a coating thereon with a surface lying in said plane, said nozzle orifice being of small dimension in the direction of motion of said arm and being extended transversely so as to apply plastic material in a wide stripe, the plane of movement of said nozzle orifice being parallel to edges of said frames at one side, and smoothing plates pivoted to said nozzle and controlled by members riding on said edges so as to be maintained parallel to the plane of movement of the nozzle orifice throughout the greater portion of the swinging motion of said arm, said frames beyond said parallel edges having edges at right angles thereto, and the members riding on said edges being adapted to pass beyond the ends of said parallel edges at each extremity of the rocking motion of said arm, and onto said right angle edges to bring the plates controlled thereby to positions at right angles to said plane.

7. In a plastering machine, a head mechanism comprising spaced members, a slotted arm lying therebetween and pivoted on means passing through the slot in said arm and fixed in said members, a threaded shaft journaled on said members and bearing a nut with a slotted extension, a pivot on said arm engaging in said slotted extension whereby movement of the nut along the shaft will cause said arm to rock about said first mentioned pivot, a cam track in one at least of said members in which said last mentioned pivot on said arm engages, a nozzle on the end of said arm remote from said first pivot, said cam track acting to produce longitudinal movement of said arm with respect to said first mentioned pivot during its rocking motion thereabout whereby the orifice of said nozzle follows a path lying in a flat plane, and means for rotating said shaft so as to produce rocking movement of said arm so that when plastic material is forced through said nozzle it is applied thereby to a wall or the like to form a coating thereon with a surface lying in said plane, said nozzle orifice being of small dimension in the direction of motion of said arm and being extended transversely so as to apply plastic material in a wide stripe, the plane of movement of said nozzle orifice being parallel to edges of said frames at one side, and smoothing plates pivoted to said nozzle and controlled by members riding on said edges so as to be maintained parallel to the plane of movement of the nozzle orifice throughout the greater portion of the swinging motion of said arm, said frames beyond said parallel edges having edges at right angles thereto, and the members riding on said edges being adapted to pass beyond the ends of said parallel edges at each extremity of the rocking motion of said arm, and onto said right angle edges to bring the plates controlled thereby to positions at right angles to said plane, said nozzle being in the form of a hollow member having means for the supplying of plastic material thereto, said plates being interconnected by resilient means passing through a lined perforation in said nozzle.

8. In a plastering machine, the combination of a vertically extending supporting means which may be juxtaposed to a wall, a head mounted for vertical sliding movement in said supporting means, means for moving said head up and down therein, an arm journaled in said head, a nozzle having an orifice mounted on the end of said arm, means on said head for moving said arm with

11

a rocking motion, means on said head for constraining the motion of said arm to cause said nozzle to traverse during said rocking movement a path lying in a flat plane, means for supplying plastic material to said nozzle and means for concurrently controlling said head and arm moving means so as to cause said nozzle to traverse a vertical surface of greater length than the height of said head and the height of said supporting means.

9. In a plastering machine, the combination of a vertically extending supporting means which may be juxtaposed to a wall, a head mounted for vertical sliding movement in said supporting means, means for moving said head up and down therein, an arm journaled in said head, a nozzle having an orifice mounted on the end of said arm, means on said head for moving said arm with a rocking motion, means on said head for constraining the motion of said arm to cause said nozzle to traverse during said rocking movement a path lying in a flat plane, means for supplying plastic material to said nozzle and means for concurrently controlling said head and arm moving means so as to cause said nozzle to traverse a vertical surface of greater length than the height of said head and the height of said supporting means, said supporting means comprising vertical trackways, a subframe mounted for sliding movement on said vertical trackways, carrying means for said head mounted for sliding movement on said subframe, said means for moving said head comprising means enforcing concurrent movement of said subframe and said carrying means for said head.

10. In a plastering machine, the combination of a vertically extending supporting means which may be juxtaposed to a wall, a head mounted for vertical sliding movement in said supporting means, means for moving said head up and down therein, an arm journaled in said head, a nozzle having an orifice mounted on the end of said arm, means on said head for moving said arm with a rocking motion, means on said head for constraining the motion of said arm to cause said nozzle to traverse during said rocking movement a path lying in a flat plane, means for supplying plastic material to said nozzle and means for concurrently controlling said head and arm moving means so as to cause said nozzle to traverse a vertical surface of greater length than the height of said head and the height of said supporting means, said supporting means comprising vertical trackways, a subframe mounted for sliding movement on said vertical trackways, carrying means for said head mounted for sliding movement on said subframe, said means for moving said head comprising means enforcing concurrent movement of said subframe and said carrying means for said head, said nozzle having smoothing plates pivoted to each side of its orifice and means for controlling said smoothing plates to keep them in a vertical plane excepting at the ends of the traverse of said arm.

11. In a plastering machine, the combination of a vertically extending supporting means which may be juxtaposed to a wall, a head mounted for vertical sliding movement in said supporting means, means for moving said head up and down therein, an arm journaled in said head, a nozzle having an orifice mounted on the end of said arm, means on said head for moving said arm with a rocking motion, means on said head for constraining the motion of said arm to cause said nozzle to traverse during said rocking movement a path lying in a flat plane, means for

12

supplying plastic material to said nozzle and means for concurrently controlling said head and arm moving means so as to cause said nozzle to traverse a vertical surface of greater length than the height of said head and the height of said supporting means, said supporting means comprising vertical trackways, a subframe mounted for sliding movement of said vertical trackways, carrying means for said head mounted for sliding movement on said subframe, said means for moving said head comprising means enforcing concurrent movement of said subframe and said carrying means for said head, said nozzle having smoothing plates pivoted to each side of its orifice and means for controlling said smoothing plates to keep them in a vertical plane excepting at the ends of the traverse of said arm, said head being mountable on said head carrying means in an additional position in which the path of movement of said nozzle orifice lies in a horizontal plane.

12. In a plastering device or the like, the combination of a portable main framework, a subframe slidable thereon, a head carrying means slidable on said subframe, a motor on said main frame, transmission means between said motor and said subframe, and between said subframe and said head carrying means whereby operation of said motor produces concurrently a movement of said subframe with respect to said main frame, and a movement of said head carrying means with respect to said subframe, and a plastering device comprising a head, a nozzle having an orifice mounted with respect to said head for planar movement of said orifice, a motor for actuating said nozzle, and means for controlling said motors to produce concurrent movement of all of said elements with respect to each other for effecting a plastering stroke.

13. In a plastering device or the like, the combination of a portable main framework, a subframe slidable thereon, a head carrying means slidable on said subframe, a motor on said main frame, transmission means between said motor and said subframe, and between said subframe and said head carrying means whereby operation of said motor produces concurrently a movement of said subframe with respect to said main frame, and a movement of said head carrying means with respect to said subframe, and a plastering device comprising a head, a nozzle having an orifice mounted with respect to said head for planar movement of said orifice, a motor for actuating said nozzle, and means for controlling said motors to produce concurrent movement of all of said elements with respect to each other for effecting a plastering stroke, said nozzle having smoothing plates pivoted to the orifice thereof, and means for causing said smoothing plates to remain in the plane of movement of said nozzle end during the stroke thereof.

14. In a plastering device or the like, the combination of a portable main framework, a subframe slidable thereon, a head carrying means slidable on said subframe, a motor on said main frame, transmission means between said motor and said subframe, and between said subframe and said head carrying means whereby operation of said motor produces concurrently a movement of said subframe with respect to said main frame, and a movement of said head carrying means with respect to said subframe, and a plastering device comprising a head, a nozzle having an orifice mounted with respect to said head for planar movement of said orifice, a motor for actuating said nozzle, and means for controlling said

motors to produce concurrent movement of all of said elements with respect to each other for effecting a plastering stroke, said nozzle having smoothing plates pivoted to the orifice thereof, and means for causing said smoothing plates to remain in the plane of movement of said nozzle end during the stroke thereof, excepting at the ends of said stroke, and means effective at the ends of said strokes for causing a leading one of said smoothing plates to assume a position at right angles to said plane.

15. In a plastering device or the like, the combination of a portable main framework, a sub-frame slidable thereon, a head carrying means slidable on said subframe, a motor on said main frame, transmission means between said motor and said subframe, and between said subframe and said head carrying means whereby operation of said motor produces concurrently a movement of said subframe with respect to said main frame, and a movement of said head carrying means with respect to said subframe, and a plastering device comprising a head, a nozzle having an orifice mounted with respect to said head for planar movement of said orifice, a motor for actuating said nozzle, and means for controlling said motor to produce concurrent movement of all of said elements with respect to each other

for effecting a plastering stroke, said nozzle having smoothing plates pivoted to the orifice thereof, and means for causing said smoothing plates to remain in the plane of movement of said nozzle end during the stroke thereof, excepting at the ends of said stroke, and means effective at the ends of said strokes for causing a leading one of said smoothing plates to assume a position at right angles to said plane, and means for supplying plastic material under pressure to said nozzle, said means comprising flexible tubing and pump means.

ABE SALMAN.
MALCOLM B. BARTLETT.
